The ornamental design for a periodical stand with monitor, as shown and described.

DESCRIPTION

FIG. 1 is an isometric view of the periodical stand with monitor showing our new design.

FIG. 2 is a front elevation view.

FIG. 3 is a left side elevation view.

FIG. 4 is a right side elevation view.

FIG. 5 is a plan view; and,

FIG. 6 is an enlarged view of the shelving portion of our new design.

The bottom of the periodical stand with monitor is flat and devoid of surface ornamentation. The rear of the periodical stand with monitor is devoid of surface ornamentation.

The dashed broken lines of FIGS. 1-6 are shown for the purpose of illustrating unclaimed portions of the periodical stand with monitor and form no part of the claimed design. The dot-dash lines shown in FIGS. 1 and 6 are for the purpose of identifying an enlargement view and form no part of the claimed design.

The article is a stand for distributing periodicals, such as newspapers, with a monitor for display of advertisements.
